GOVERNOR FOR IMPACT WRENCHES

Lester A. Amtsberg, Cleveland, Ohio, assignor to
 Chicago Pneumatic Tool Company, New York,
 N. Y., a corporation of New Jersey

Application September 28, 1940, Serial No. 358,802

7 Claims. (Cl. 121—34)

This invention relates to governors for controlling the speed of motors and has particular, but not exclusive, application to impact wrenches driven by rotary air motors.

Impact clutches are usually designed to respond to the torque requirement of the driven bolt or nut, whereby during the free running period the clutch imparts continuous or substantially continuous rotation, and under conditions of excessive torsional resistance the clutch operates to effect a series of disengagements and impacts. During the impacting cycle it is desirable to supply the motor with increased power thereby increasing the motor torque, the acceleration of the rotary hammer assembly, and the force of the blow.

An object of this invention is to limit the free running speed of an impact wrench, without interfering with the speed of the motor, or the supply of power thereto, during the impacting cycle.

Another object is to throttle the air supply to the rotary engine while the impact clutch is imparting continuous rotation, by means of a governor which is rendered ineffective during the impacting cycle.

Further objects are to reduce air consumption, to increase the force of the blow, to provide a wider range of speed control and to prolong the life of the movable parts of the wrench.

In accordance with the above and other objects, this invention provides a governor which is driven by the anvil element of the impact clutch instead of by the driving motor, as in prior constructions. Thus the governor responds to the motor speed as long as the clutch drives the anvil continuously, but falls below the motor speed and thereby becomes ineffective when the clutch begins impacting and the driving element of the clutch makes a much greater number of rotations than the driven or anvil member.

In the accompanying drawings which illustrate one embodiment of the invention:

Fig. 1 is a longitudinal section of a reversible rotary impact wrench provided with the governor arrangement of the present invention, parts of the supporting handles being broken off;

Fig. 2 is a cross section through the impact clutch, as indicated by the arrows 2 in Fig. 1, illustrating the relation between the hammer dogs and the driving means therefor;

Fig. 3 is a cross section through the impact clutch, as indicated by the arrows 3—3 of Fig. 1, showing the hammer dogs out of driving engagement with the anvil;

Fig. 4 is a view similar to Fig. 3, showing the hammer dogs in the driving or impact delivering position, parts of the carrier for the dogs being omitted;

5 Fig. 5 is a view, chiefly in longitudinal section, showing the centrifugal governor, the control valve operated thereby, and the elements which drive the governor;

Fig. 6 is an elevational view, looking forward, 10 showing one of the governor weights in operative relation with the associated carrier and push pin, a part of the latter being broken away; and

Fig. 7 is a cross section through the rotary air motor and reversing valve, as indicated by the arrows 7 in Fig. 1.

Figs. 5 and 6 are on a considerably larger scale than any of the remaining figures and show the governor actuated to a position which limits the flow of live air.

The invention is illustrated as applied to an impact wrench of the type in which the motor is directly connected to the clutch hammer assembly, whereby the motor repeatedly starts and stops during the impact cycle.

Referring particularly to Fig. 1, the illustrative impact wrench comprises a governor housing 10, a motor housing 11, and a clutch housing 12, all detachably secured in fixed relation by any suitable means such as the usual arrangement of bolts and flanges (not shown). The motor housing supports, on opposite sides, a dead handle 13 and a throttle valve handle 14 through which live motive fluid such as compressed air is admitted to the impact wrench. The top of the governor housing is bolted to a spade handle 15. Still another means of support for the impact wrench resides in the front end of the clutch housing which is tapered to provide a grip portion 12a.

A reversible air motor 17 within the motor housing 11 includes a cylinder or cylinder liner 18, the ends of which abut against end plates 19. The rear end plate has a peripheral portion fitting the motor housing 11 and clamped between the cylinder 18 and governor housing 10. A gasket 20 may be interposed between the governor housing and the motor elements which include the motor housing 11, cylinder 18 and rear end plate 19. The end plates are provided with annular flanges 21 projecting away from the cylinder and supporting ball bearings 22 for the shafts of a rotor 23. The body of the rotor is in the form of a cylinder coaxial with the ball bearings 22 and defined by the end plates 19. As shown in Fig. 7, the cylinder 18 is arranged eccentrically

with respect to the axis of rotor 23, thus defining a crescent-shaped chamber 24 therebetween. Arcuate slots 25 near the ends of the crescent-shaped chamber provide means for the admission and exhaust of pressure fluid thereto. The rotor has radial slots extending from end to end thereof in which blades 27 are mounted for inward and outward movement relative to the rotor while the outer edges of the blades are maintained in contact with the inner wall of the cylinder. The blades divide the crescent-shaped chamber 24 into a series of pockets, each of which is arranged to receive live air, disconnect the air from its source, expand in size as it revolves under the influence of the live air, exhaust 15 the motive fluid after the pocket has obtained maximum size, and then diminish in size. In order that the inlet and exhaust may be properly timed without interfering with the reversibility of the engine, a set of relief ports or auxiliary 20 exhaust ports 29 is provided on each side of the cylinder. The function of these sets of ports is to increase the effective length of the arcuate slots 25 which happen to be on the exhaust side, but not the slots on the inlet side. This is accomplished by a spring pressed plate 30 associated with each set of auxiliary exhaust ports and mounted for pivotal movement. The plate is movable out of the path of the ports 29 under 25 the influence of the air being exhausted through said ports. On the inlet side, the valve 30 is held in a position closing the ports 29, under the combined influence of spring and live air pressure.

The direction of rotation of the engine is controlled by a reversing valve 32 (Figs. 1 and 7) mounted to turn in a bushing 33 seated in a recess at the side of the motor housing 11. The bushing has an inlet port 34 and an exhaust 40 port 35 and the reverse valve has a pair of recesses adapted selectively to connect inlet port 34 with one of the motor ports 36 or 37 and the exhaust port 35 with the other motor port. The reverse valve is manipulated by a lever 38 and is yieldingly locked in either extreme position 45 by springs 39.

The impact clutch comprises an anvil 40 having impact receiving jaws 41, and a pair of hammer dogs 42 which are mounted for limited oscillatory movement about respective pivot pins 43. The front portion of the anvil projects beyond the clutch housing and is adapted for attachment at its extremity to wrench socket 45 for driving a threaded nut N. The front end of the clutch housing is counterbored to receive a resilient bushing 46 made of oil resisting synthetic rubber. The resilient bushing supports a steel bushing 47 which provides a bearing for the front portion of the anvil 40, the arrangement being such as to relieve the clutch housing of shocks transmitted to the anvil member. The rear end of the anvil is recessed to receive a pilot shaft 48 which has a loose fit in said recess as well as in a similar recess at the front extremity of the shaft for the rotor 23 whereby the anvil is held in axial alignment with the rotor but is not always constrained to rotate in unison therewith.

The hammer assembly comprises front and rear carrier plates 49 and 50 respectively which 70 support the ends of the pivot pins. A pair of spacer sleeves 51 (Figs. 1 and 3) also extend between the carrier plates and are bolted thereto. The spacer sleeves, carrier plates and pivot pins form a substantially rigid structure, resembling 75

a squirrel cage, which revolves about the axis of the anvil 40. The plates 49 and 50 are centrally bored to receive bushings 52. The front plate 49 is held between the front end of the jaws 41 and a washer 53 seated on an annular flange at the rear end of the steel bushing 47. Washer 53 also serves as a retainer for the heads of the pivot pins 48.

The rear plate 50 surrounds the cylindrical portion of a driving cam 54 and rotates approximately in unison with the cam as will be herein-after pointed out. The cam has a splined connection with the front end of the rotor shaft. Suitable washers 55 and 56 hold the cam and hammer assembly against axial movement relative to the anvil 40 and clutch housing 12. The hammer assembly is driven by a force acting on each of the dogs 42 in a direction offset from the pivotal axis thereof, whereby the driving force tends to rock the dog in a declutching direction. In front of the plate 50, the cam 54 has a pair of arms 57 seated in sockets 58 in the hammer dogs 42. In front of the sockets 58, the dogs 42 are provided with internal cam surfaces 59 adapted to ride over the anvil jaws 41, as the hammer assembly rotates ahead of the anvil, and rock the dog about the pivot pin 43 in a re-clutching direction. The center of gravity of the dog preferably lies within the path circumscribed by the axes of the pivot pins 43 so that when the dog is rocked to one extreme position or the other, it tends to remain there by centrifugal force.

Assuming that the motor 17 is rotating continuously and the resistance to rotation of the driven nut N is slight, the rotor 23, driving cam 54, hammer dogs 42 and anvil member 40 all rotate substantially in unison in the position shown in Fig. 4, relative movement between the clutch elements being resisted by friction and centrifugal force. The clutch will disengage occasionally even under very light loads, but each disengagement will be followed by a re-engagement since the dogs are constrained to move in a re-clutching direction following each disengagement. When the driven nut N becomes seated against one of the elements being secured, the resistance to further rotation rises to a point far in excess of the torque of the motor. The impact clutch is then effective to cause the delivery of rotational impulses or hammer blows greatly exceeding the maximum motor torque. When a blow is delivered, the momentum of the driving assembly including the hammer dogs 42, carrier plates 49 and 50, and the rotor 23 is transferred in a very brief instant to the anvil and the motor is temporarily stalled. The driving cam 54 then rocks the dog 42 in a declutching direction about the axis of the stationary pin 43. The complementary cam elements 41 and 59 then rock the dog back to the Fig. 4 position for delivering a succeeding hammer blow. For a further description of the structure and operation of the impact clutch per se, reference is made to applicant's copending application Serial No. 305,708, filed November 22, 1939, which contains claims to the impact clutch and also to the resiliently mounted bushing 47 disclosed in the present application.

The usual impact wrench is driven by a motor arranged to operate at a speed of about 3000 revolutions per minute. It has been found desirable in some instances, particularly in the case of a wrench of large size, to reduce the speed to a comparatively low value, such as 800

or 500 R. P. M. The adjustment of the conventional governor arrangement to slow speed, however, has the disadvantage in that it limits the supply of air, and hence the force of the blow, during the impact cycle—that is, after the nut or bolt has been seated and the motor runs with a rapid succession of lost-motion periods, each followed by an impact. In order to limit the run-up or free speed of the motor and yet permit impacting with the governor valve wide open, the present invention involves the novel arrangement of a governor assembly driven by the anvil instead of by the motor.

Referring to Figs. 1 and 5, the governor rod 60 is disposed coaxially with the rotor 23 and anvil 40 and extends throughout practically the entire length of the motor and clutch housing. The lower extremity of the rod is secured to a hexagonal shank 61 by means which include a pin 62 and a brazing connection. The shank 61 fits a hexagonal opening in the anvil 40 and enables the rod 60 to be driven thereby. A sleeve 63 surrounds the rod 60 and spaces the pilot shaft 48 from the hexagonal shank. The upper end of rod 60 has a splined connection with a governor body 64 which is seated for relative turning movement in a recess at the rear extremity of the shaft for the rotor 23. The governor body is provided with two oppositely extending pairs of parallel arms 65 which support transverse pins 66 on which governor weights 67 are pivoted. The weights are provided with projections 68 engaging under a transverse bar 69 at the upper end of a push pin 70. The push pin 70 is mounted in a recess at the rear end of governor body 64 and is arranged to be moved relative to the governor body in a rearward direction by the centrifugal weights or in a forward direction by air pressure. The push pin abuts against the front end of a stem portion 71 on a governor valve 72 which is coaxial with the push pin and reciprocates in unison therewith.

Governor valve 72 is mounted in a cage 73 which is screw threaded to the governor housing 10. A stop pin 75 extending diametrically across the rear portion of the cage limits rearward movement of the valve 72. The governor cage 73 is open continuously at its rear end for the admission of live motive fluid, and is provided with one or more peripheral ports 76 by means of which said motive fluid may escape under the regulation of the governor valve. The valve thus controls the flow of air through a circuit beginning with a throttle valve (not shown) in the throttle handle 14, the bore in said handle, registering passages 78 and 79 in the motor housing and the governor housing respectively, the rearwardly open bore of governor cage 73, outlet ports 76, governor housing passageway 80, and ports 81 and 34 entering the reverse valve 32 which admits air to one side of the motor 17 and exhausts the other side as hereinbefore described. The governor valve 72 is provided with longitudinal ports 83 which balance the air pressures at the rear and front, with the exception of the area occupied by the stem portion 71. The unbalanced area at the rear of the governor valve 72 moves the valve and the push pin 70 forward in opposition to the thrust of the centrifugal weights 67 until a balance is attained between fluid pressure and centrifugal force. By uncovering more or less of the area of the governor outlet ports 76, the governor controls the speed of the anvil 40 within reasonably close limits. Any tendency of the anvil 40 to exceed

the maximum predetermined speed increases the centrifugal force acting rearwardly on valve 72 and thereby reduces the size of the uncovered area of the ports 76, and consequently the rate of flow of pressure fluid to the motor and the speed of the latter. Conversely, a reduction in speed of the anvil 40 increases the opening at the ports 76 and, if the motor is unable to drive the anvil at the predetermined maximum speed, the openings 76 remain wide open. The selected speed can be adjusted by changing the weights 67.

Briefly summarizing the operation, let it be assumed that the governor is arranged to limit the anvil speed to 800 R. P. M. and that the socket 45 is starting to run up a nut offering at the time very little resistance to rotation. The operator opens the throttle valve (not shown) in handle 14 admitting live air past the governor valve 72 and reverse valve 32 to the motor 17 to rotate the latter in a clockwise direction looking forward. As long as the resistance to rotation is slight, the rotor 23, hammer carrier 49 and 50, hammer dogs 42, anvil 40, wrench socket 45 and driven nut N all rotate in unison with the parts in the Fig. 4 position. As the anvil starts to rotate, the governor valve 72 starts from its fully open position and moves rearward under the influence of the centrifugal weights 67 until it reduces the size of the opening 76 to the extent that the anvil speed is held to 800 R. P. M. The motor speed will be the same except for an occasional rise above this amount when the impact clutch releases and permits the motor to make a half turn ahead of the anvil and then re-engages. When the driven nut N becomes seated and its resistance to further rotation increases abruptly, the hammer dogs 42 are released from the anvil by a cam action and move from the engaged position shown in Fig. 4 to the lost motion position shown in Fig. 3. The action of the complementary cams 59 and 41 restores the hammer dogs to the Fig. 4 position, the re-engagement between the dogs and the anvil being accompanied by an impact having a torsional force greatly exceeding the maximum torque of the motor. The disengagement and re-engagement of the clutch is repeated and the impacts are delivered in rapid succession.

The action of the motor during the impact cycle is to start and stop each time an impact is delivered, the motor making a half turn at a time. The acceleration of a rotary air motor under these conditions is very great and the instantaneous speed of the motor may exceed 800 R. P. M. before the rotor has moved 180° from its stalled position. In order to obtain maximum force of blow, it is desirable to disable the governor, or speed limiting mechanism, during the impacting cycle and permit the governor ports 76 to remain wide open during this period. The present invention accomplishes this end without interfering with the operation of the governor during the running-up period, by driving the governor from the anvil, instead of from the motor as in prior constructions. The anvil does not move the governor valve to partly closed position during the impacting cycle because the mean speed and the maximum instantaneous speed of the anvil are both much lower than the corresponding speeds of the motor.

When the operator desires to loosen a bolt or nut, he turns the reverse valve 32 to its opposite position, places the socket 45 over the bolt or nut and then opens the throttle valve. The operation is similar to the action above described, but

the parts revolve in a counterclockwise direction and the impact cycle precedes the free running period of the clutch. While the clutch is impacting, the governor controlled valve 72 remains wide open. After the nut has been loosened and while the removal is opposed by only a slight amount of friction, the valve 72 partly closes to prevent the nut from being run off at an objectionably high speed.

What is claimed is:

1. An impact wrench comprising an anvil adapted to drive a threaded securing member, a rotary impact hammer arranged to drive said anvil and deliver a series of rotational hammer blows thereto, a fluid pressure rotary engine for driving said hammer, and a centrifugal governor for controlling said engine, characterized by operating means for said governor driven by the anvil.
2. An impact wrench comprising a rotatable anvil, a rotatable impact hammer arranged to drive said anvil, clutch means between the hammer and anvil for causing a succession of disengagements and re-engagements therebetween, a rotary motor for driving said hammer, governor means for limiting the speed of the motor while the hammer is in driving engagement with the anvil, and means for rendering the governor means ineffective while the hammer is disengaged from the anvil.
3. A wrench comprising a rotary air motor provided with a rotor, a releasing clutch having a driving element rotatable substantially in unison with the rotor and having a driven element adapted to be attached to a wrench socket, a governor for throttling the air supply to said motor, said governor comprising a valve urged toward closed position by centrifugal means, characterized by operating means for said centrifugal means driven by the driven element of the clutch.
4. A wrench comprising a rotary air motor provided with a rotor, a releasing clutch having a driving element rotatable substantially in unison with the rotor and having a driven element adapted to be attached to a wrench socket, a governor for throttling the air supply to said

motor, said governor comprising a valve urged toward open position by compressed air and toward closed position by centrifugal means, characterized by operating means for said centrifugal means driven by the driven element of the clutch.

5. In a device of the character described, a rotary motor, a conduit for supplying power thereto, governor means interposing a variable resistance in said conduit to the power supply for controlling the speed of the motor, a clutch having a driving element connected to the motor and having a driven element arranged to be disconnected periodically from the driving element to enable the motor at times to rotate faster than the driven element, and a driving connection between the driven element and the governor means.

6. An impact wrench comprising a rotary motor, a conduit for supplying power thereto, governor means interposing a variable resistance in said conduit to the power supply to control the speed of the motor, an impact clutch driven by the motor and including a hammer arranged under certain conditions to rotate in unison with the anvil and under other conditions to repeatedly rotate ahead of the anvil and deliver impacts, and a driving connection between the motor and governor for limiting the motor speed while the hammer and anvil rotate in unison, characterized in that said driving connection is arranged to be broken to remove the restriction on the power supply during the time that the hammer is rotating ahead of the anvil.

7. A power operated wrench comprising a centrifugal governor, a rotary air motor positioned in front of said governor and controlled thereby, a clutch in front of said rotary air motor, said clutch including a driving element adapted to be driven by the motor and a driven element to be driven by the driving element, said clutch elements being arranged coaxially with the motor and governor, and a driving connection between the clutch driven element and the governor, said driving connection comprising a rod extending through aligned bores in the driven element and motor.

LESTER A. AMTSBERG.
